US00D905119S

(12) **United States Design Patent** (10) Patent No.: **US D905,119 S**
(45) Date of Patent: **** Dec. 15, 2020**

(54) **AIR PUMP**

(71) Applicant: **Hao Wang**, Guangdong (CN)

(72) Inventor: **Hao Wang**, Guangdong (CN)

(**) Term: **15 Years**

(21) Appl. No.: **29/695,369**

(22) Filed: **Jun. 18, 2019**

(30) **Foreign Application Priority Data**

Dec. 18, 2018 (CN) 2018 3 0734366

(51) LOC (12) Cl. **15-02**

(52) U.S. Cl.

USPC **D15/7**

(57) **CLAIM**

The ornamental design for an air pump, as shown and described.

DESCRIPTION

FIG. 1 is a front elevational view of an air pump showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top and rear perspective view thereof;

FIG. 8 is a top, front and right side perspective view thereof;

FIG. 9 is a bottom, rear and right side perspective view thereof; and,

FIG. 10 is a bottom, rear and left side perspective view thereof.

The broken lines depict portions of an air pump and form no part of the claimed design.

1 Claim, 10 Drawing Sheets
